UNITED STATES PATENT OFFICE.

ROBERT E. DETTE, OF KNOXVILLE BOROUGH, PENNSYLVANIA.

BORING-TOOL.

981,392.

Specification of Letters Patent. Patented Jan. 10, 1911.

Application filed December 20, 1909. Serial No. 534,097.

To all whom it may concern:

Be it known that I, ROBERT E. DETTE, a citizen of the United States, residing at Knoxville borough, in the county of Allegheny and State of Pennsylvania, have invented certain new and useful Improvements in Boring-Tools, of which the following is a specification, reference being had therein to the accompanying drawing.

10 My invention consists of an improvement in boring tools and has for its object to provide a tool having a plurality of sets of cutters, *i. e.* roughing cutters and finishing cutters, arranged longitudinally of its 15 length, located at suitable intervals and adapted to operate together successively through a rough opening in metal, as the hub of a car wheel.

20 My improved tool is particularly designed for the purpose of rough boring and finishing the work simultaneously by means of the several cutters, obviating the necessity of feeding the tool through the bore twice, as is now common practice with other types 25 of boring tools in use in similar work.

The tool consists generally of a main shank portion having the laterally arranged roughing cutters and finishing cutters, and incidentally an ordinary filleting cutter, the 30 rough and finishing cutters being adapted to ready and accurate adjustment to cut several predetermined sizes of bore, with means for accurate and minute adjustment, in the manner more fully hereinafter described.

35 Referring to the drawings;—Figure 1 is a view of the boring bar in side elevation. Fig. 2 is a view of the boring bar at right angles to Fig. 1, partly in section on the line II. II. of Fig. 1. Fig. 3 is a similar view, 40 in a position corresponding to Fig. 1, but partly in section on the line of III. III. of Fig. 2. Fig. 4 is an enlarged detail view of the adjusting key for the finishing cutters and its locking latch. Fig. 5 is a cross-sectional detail view on the line V. V. of Fig. 2 showing the means for adjusting the finishing cutters. Fig. 6 is a similar sectional view on the line VI. VI. of Fig. 2, showing 45 the roughing cutters and the sizing plug therefor. Fig. 7 is a similar view on the line VII. VII. of Fig. 2 showing the filleting cutter and its holding screw. Fig. 8 is a sectional view of the lower end of the bar similar to Fig. 2, but showing a modified 50 construction of sizing and adjusting mecha-

nism for the finishing cutters. Fig. 9 is a cross sectional view on the line IX. IX. of Fig. 8. Fig. 10 is a vertical sectional view on the line X. X. of Fig. 8. Fig. 11 is a detail view enlarged, of the adjusting screw 60 for the finishing cutters of Fig. 2. Figs. 12 and 13 are detail views of one of the adjustable bushings with its stem extension and the sizing block as used therewith. Fig. 14 is a detail view of said sizing block. Fig. 15 65 is a similar view of the sizing plug for the roughing cutters.

In the drawings, 2 represents the main body portion of the tool which is generally cylindrical in form and provided at its upper portion with a reduced tapered extremity 3 for insertion in the actuating head of the boring mill or machine.

At its lower portion the bar is provided with a pair of laterally arranged roughing 75 cutters 4, and finishing cutters 5. 5. arranged midway between said roughing cutters, laterally of the bar 2 in suitable receiving cavities or recesses therein, the finishing cutters preferably over-lapping 80 downwardly across the working peripheral area of the roughing cutters 4.

6 represents a finishing filleting cutter located in a suitable socket at any desired position beyond the finishing cutter, adjustable outwardly by temper screw 7 and secured in position by a set screw 8, said filleting cutter however, forming no part of the present invention.

The construction of the roughing cutters 90 is such as to permit of positive adjustment to make a rough cut of any predetermined or desired dimension readily and quickly for which purpose I employ a sizing plug 9 which is inserted and adjusted by the hand 95 of the operator transversely of the bar within a cylindrical opening 10 therein.

The sizing plug 9 has a main cylindrical body portion composed of short end cylinders 11 and intervening narrow collars or 100 flanges 12 of the same diameter, all of which bear within the transverse cylindrical opening 10.

The body portion of the sizing plug between its end cylindrical portions 11 and 105 collars 12 and the central body portion between said collars is made rectangular as shown, providing sets of bearing faces 13, 14 and 15, each set comprising four rectangularly arranged faces, comprising two 110

bearings, of two different widths apart. That is to say, the opposite faces 13 are of a predetermined distance apart and equally from the center, while the intervening faces 5 are of a different distance apart and from the center. The sets of faces 14 and 15 are similarly arranged by which construction I secure three successive four-sided sets of faces of increasing dimensions as to width 10 comprising altogether six independent sets of faces. By registering any one of the set of faces *i. e.* opposite sides, with the back ends of the roughing cutters 4, for instance the closest faces of the set 15, the roughing 15 cutters may be set inwardly to their closest position for making a minimum cut.

By rotating the sizing block one fourth rotation the intervening or adjacent faces are brought into bearing position, thus locating the roughing cutters outwardly to the next desired size. By shifting the sizing plug longitudinally the next set of faces 14 are brought into register with the ends of the roughing cutters, said faces 14 operating in the same way to successively adjust the roughing cutters for increasing diameters of cuts, the third set of faces 13 being adjusted in the same way. By this means I secure altogether six different 30 adjustments by varying the location of the sizing plug, *i. e.* by pulling it out, leaving in center, or pushing it in, giving three different sizes; or by turning the sizing plug one fourth way around and then similarly 35 locating it, giving three additional sizes.

As indicated in Fig. 15, the end of the sizing plug is marked appropriately so that by arranging the plug whereby the reading will align with the direction of the roughing 40 cutters and locating the opposite bearing faces 13, 14 or 15 in register with the cutters, the desired diameter of the roughing cut is readily determined. The roughing cutters, after being thus located with relation to the sizing plug and set inwardly 45 thereagainst by their inner ends, are then tightened in position by means of set screws 16 and a transverse bearing bar 17 engaging the underside of both cutters 4, as shown in 50 Fig. 10.

In the construction shown in sheet 1 of the drawings the finishing cutters 5 are inserted and held by set screws in the receiving slots in the ends of cylindrical cutter 55 holders 18, 18, which in turn are mounted in a cylindrical receiving cavity 19 arranged transversely of the bar 2 above cavity 10 and in alignment therewith, and transversely mid-way of the roughing cutters 4. The 60 cutters 5 are braced by the sides 31 of suitable receiving slots.

Cutter holders 18 are centrally threaded with right and left-hand threads as indicated at 20 and are engaged by the similarly 65 arranged threads of an adjusting screw 21,

at the middle portion of which are secured a beveled gear wheel 22 and a beveled oppositely arranged backing collar 23.

24 is an adjusting gear mounted in cavity 25 in bar 2 opposite the middle portion of 70 the cutter holder cavity 19, and having a head 26 provided with a turning socket 27 for the reception of an adjusting key.

28 is a helical spring inserted in cavity 25 and bearing outwardly against a collar 75 29 on adjusting screw 24 for throwing it outwardly.

In using the above described construction the roughing cutters are set to the position for making the roughing cut desired by 80 manipulation or positioning of the sizing plug 9, as has been described, the cutters then being retained in place by set screws 16 and bar 17.

The finishing cutters are adjusted by 85 means of the adjusting gear-toothed key 24 which bears backwardly against the retaining collar 23 whereby the key 24 is maintained in substantially central position with slight lost motion, due to clearance of the 90 teeth of adjusting screw 24 between gear 22 and collar 23. By turning the adjusting screw 24 to the right or left the cutting edges of cutters 5 may be accurately and minutely set to the desired position, either 95 to make the finishing cut initially, or to take up any wear, and will there remain, due to the holding action of the screws and gears and the retaining effect of the latch 30. Said latch is slidably mounted in a receiving 100 socket above the head 26 of key 24 and bears against it as shown to retain the key in place when lowered, allowing the key to be removed when the latch is raised.

The operation of the bar will be readily 105 understood from the foregoing description.

In the construction shown in Figs. 8, 9 and 10 the roughing cutters are mounted and operated in the same manner as before described. The finishing cutters 5' are inserted in receiving slots in the ends of the cylindrical cutter holders 18' and are also held therein and braced as are cutters 18. For the purpose of adjusting the cutters 5' of this construction to the desired operating 115 position, each holder 18' is internally threaded as indicated at 33, and each receives a correspondingly threaded adjusting bushing 34. The edge of the head of each bushing is serrated or notched as indicated at 35 120 (Figs. 12 and 13) one of said bushings having an extended stem 36 divided as at 37 for binding resiliently within a suitable receiving centrally arranged socket 38 in the other bushing 34' shown in Fig. 8. Each bushing 125 34 and 34' is provided with suitable turning spanner holes 39, and after adjustment is secured in its proper cutter holder 18' by a set screw 39 engaging one of the notches 35. By this means the inner face of the 130

head of bushing 34 is set outwardly or inwardly with relation to its cutter holder 18' so that when positioned in the cavity 19' of the bar, and separated by any suitable 5 abutment, as the sizing block 40, its inward travel to locate the cutting edges of cutters 5' to the desired position will be limited. The sizing block 40 is similar in function to the sizing block 9 for the roughing cutters, 10 and is generally cube-like in form and dimensioned as to the distance between the opposite faces thereof so as to provide for three different sizes *i. e.* of three different pairs of oppositely arranged bearing faces of 15 varying distances apart. The said sizing block is also provided with centrally arranged transverse openings 41 perforating each face through the body of the block from side to side for clearance of the split 20 stem 36. The sizing block is also provided on its faces with dimension marks arranged parallel with the direction of the hole through which the split tension pin 36 is to pass (see Fig. 14) whereby the block is thus 25 located readily for location of the finishing cutters to any pre-determined distension or fixed position. This block may bear on three of its faces 6 15/16, 7 and 7 1/16 indicating that when the block is properly placed the 30 cutters will be located to make the cut corresponding to the dimensions indicated.

For the purpose of holding the cutters 5' in substantially central position and preventing undue movement of their holders 18' 35 laterally while still allowing for a limited amount of "floating" movement, the pin 32 of a locking key 42 engages one of the openings 41 in block 40 as shown in Fig. 14. Said pin 32 is sufficiently smaller than hole 40 41 to allow a limited lateral movement of cutters 18' like that of cutters 18, to permit said cutters to properly follow the opening made by the rough cutters 4.

The key 42 is similar in construction and 45 mounting to the key 24, but not necessarily having the turning socket, its function being merely to lock the block 40 and the assembled finishing cutters.

The advantages of the invention will be 50 readily appreciated by all those familiar with this class of tools. It permits of quick and accurate adjustment of the finishing cutters without the necessity of caliperizing or other measuring operations, the finishing cutters 55 of both constructions having a sliding fit by their holders 18 or 18' in the socket of the boring bar, and being capable of a slight floating movement toward one side or the other to allow the cutters to maintain proper 60 working position through the work independent of the chatter or vibration of the piece being operated upon due to the action of the roughing cutters.

The use of the sizing plug or block with its 65 identifying dimension marks not only facil-

tates the easy and quick adjustment of the cutters, but insures accuracy and the avoidance of mistakes.

The mounting of the finishing cutters midway between the roughing cutters with their 70 cutting edges or corners stepped slightly back longitudinally from the path of the roughing cutters edges or corners provides for one practically continuous operation so that the hole is bored and finished by one 75 passage of the tool through the work.

The construction, design, or arrangement of the parts may be changed or varied by the skilled mechanic, provided such changes come within the scope of the following 80 claims.

What I claim is:—

1. A boring tool having a pair of fixed roughing cutters, a pair of finishing cutter holders located between and rearward of 85 said roughing cutters and adjustable independently thereof, finishing cutters secured in said independent holders and extending into the path of the fixed roughing cutters, and means for adjusting said holders and finishing cutters and for providing a limited amount of floating adjustment with relation to the fixed roughing cutters. 90

2. A boring tool having a pair of finishing cutters, and gearing for adjusting said finishing cutters laterally, said gearing having a slight lost motion to permit of a limited movement of the finishing cutters together. 95

3. The combination with the laterally apertured bar, of a pair of finishing cutters, 100 a screw adapted to advance or retract the finishing cutters together and provided with a gear wheel, and an adjusting device having a toothed wheel engaging said gear.

4. A boring bar having a pair of transversely arranged slidably mounted cutter holders provided with cutters, screw mechanism for adjusting said holders and cutters laterally, and means located between the holders for adjustment thereof and for allowing a slight lost motion and corresponding limited movement of the holders and cutters together. 105

5. In a boring bar, the combination with a laterally apertured bar, of oppositely arranged cutters, and holders therefor, a screw 115 engaging said holders, and means laterally disposed between the holders for actuating said screw to expand or contract the cutters.

6. In a boring bar, the combination with a laterally apertured bar, of oppositely arranged cutters, and threaded holders therefor, a screw engaging said holders having a beveled gear and a collar, and an adjusting key having a bevel gear terminal end 125 engaging said bevel gear.

7. In a boring bar, the combination with a laterally apertured bar, of oppositely arranged cutters and threaded holders therefor, a screw engaging said holders having a 130

- beveled gear and a collar, an adjusting key having a bevel gear terminal engaging said bevel gear, and means for holding said key in position.
- 5 8. A boring bar having a pair of fixed roughing cutters adapted to make an initial cut, a pair of slidingly mounted finishing cutter holders located between and rearward of said fixed roughing cutters and adjustable independently thereof, finishing cutters secured in said holders and extending into the path of the fixed roughing cutters, screw
- mechanism for adjusting said holders and cutters laterally, and means incorporated with the holders and bar, providing a 15 limited movement of the holders and cutters together with relation to the fixed roughing cutters.
- In testimony whereof I affix my signature in presence of two witnesses.
- ROBERT E. DETTE.
